(No Model.)

I. KITSEE.
FIRE ANNIHILATOR.

No. 252,678.

Patented Jan. 24, 1882.

Attest,

W. H. N. Knight

Abraham & Mayer

UNITED STATES PATENT OFFICE.

ISIDOR KITSEE, OF CINCINNATI, OHIO.

FIRE-ANNIHILATOR.

SPECIFICATION forming part of Letters Patent No. 252,678, dated January 24, 1882.

Application filed November 7, 1881. (No mod. 1.)

To all whom it may concern:

Be it known that I, ISIDOR KITSEE, a citizen of the United States, residing at Cincinnati, in the county of Hamilton and State of Ohio, have invented a new and useful Improvement 5 in Fire-Annihilators, of which the following is a specification.

My invention relates to improvements in fire-annihilators; and it consists of devices for holding in reserve magazines of chemicals, which are ejected therefrom by the melting of fusible retaining-connections into a common receptacle, and which therein commingle by natural affinity into gas or vapor, which escapes 15 through suitable eduction pipes or valves.

I have found by experience that the gases or vapors in general use for the purpose of extinguishing fires, when prepared and kept for use for any length of time in a completed condition, become liable to deteriorate, and that by keeping the several constituent chemical elements that compose such gases or vapors in 20 separate chambers, and then commingling them when required for use, the gases and vapors thus evolved are purer and more effective for 25 the purposes intended.

The object of my invention is to obviate the defects herein pointed out of keeping fire-annihilating gases or vapors always prepared in a completed condition; and in order to carry 30 out my invention, I provide suitable mechanical devices, which, when brought into action, empty the several constituent elements of fire-annihilating material into a common receptacle, where they combine and form the required vapor or gas, the several chemicals being released from their separate chambers or compartments by the melting of fusible connections, and therefrom discharged into a common 35 receptacle, wherein they commingle and combine by natural affinity and produce a required gas or vapor.

For the purpose of illustrating my invention and the manner in which it may be used and 40 operated, reference is had to the accompanying drawings, in which similar letters of reference indicate like parts.

I do not desire to limit myself to the mechanical devices shown in the drawings, as it is manifest that any device that will release separate 45 suitable chemical ingredients and eject them into a common reservoir, wherein, being brought

together, they will combine and form fire-annihilating gases, vapors, or fluids, can be used without departing from the scope of my invention. 55

In the drawings, Figure 1 represents a device by means of which my invention can be practiced.

A is a revolving cylinder, divided into two compartments, *a a'*. It is hung on trunnions *b* passing through standards *B B'*. I show only two compartments, *a a'*; but these may be increased to any required number. 60

A² A² are two sliding doors, having projections *a² a²*. *A³* is a loaded plate to control the movements of the cylinder by gravity. The cylinder is kept in the position shown in Fig. 1 by fusible wires *d d*, or wires which may be retained by fusible joints *d' d'*. 65

Instead of the suspensory wires, the cylinder may be kept in position by means of fusible keys or caps, as illustrated at *d²*, Fig. 1, or any suitable fusible connection. 70

B is a reservoir or generating-chamber, which 75 may contain any fluid or necessary ingredient that will combine with the ingredients contained in the compartments *a a'*. Springing from the generator *B* are two or more vertical spouts, *C*, open at each end, the upper openings of which are closed by the cylinder *A*, which rests thereon. 80

The generator *B* is provided with eductions *B' B²*, which may be entirely open, as shown in Fig. 2, or may be closed by easily-fusible 85 diaphragms *b²*, or have rose-caps *b³*.

In lieu of the eduction ends *B' B²*, or in addition thereto, pipes *b'* may extend from the generator and be led therefrom and branch out into any part of the building. 90

Fig. 2 is a side elevation of Fig. 1. Fig. 3 is a sectional view thereof. Fig. 4 represents parts in detail.

The operation of my device is obvious. When the chemicals are emptied from their separate apartments into a common receptacle they therein combine and compose the fire-annihilating gas or vapor, which passes out through suitable conduits and is evolved into the rooms of a building. As, for instance, suppose compartment *a* should contain sulphuric acid and compartment *a'* should contain lime, by rupture of the fusible connection *d d'* the cylinder *A* would partially rotate, the traps or doors *A²* 95 100

would strike against the spouts C and automatically open, discharging the contents of the compartments into the generator B, from whence the fire-annihilating compound generated by contact of the chemicals would pass through the eduction ends or pipes.

Connected with the operative parts may be combined any form of annunciators, electric armatures, or fire-alarms, or water-connections.

o What I claim is—

1. In a gas or vapor fire-annihilator, a magazine adapted to contain chemical ingredients in separation, held in position by fusible connections the rupture of which brings said chemicals into contact, in combination with a receiving-generator, substantially as described.

2. In a fire-annihilator, the combination of a receiving-generator having suitable induc-

tion and eduction openings with a vessel divided into compartments for storage of chemical ingredients, which, when combined, generate a required gas or vapor, substantially as described.

3. In a gas or vapor fire-annihilator, the chamber A, divided into compartments, and provided with a gravity-weight, A³, and weighted eduction-traps A², the whole sustained in position by easily-fusible connections, in combination with a receiving-generator, B, provided with suitable receiving-conduits and eduction-openings, substantially as described.

ISIDOR KITSEE.
